US00D877066S

(12) **United States Design Patent** (10) **Patent No.:** **US D877,066 S**
(45) **Date of Patent:** **** Mar. 3, 2020**

(54) **WIRELESS CHARGER**

(71) Applicant: **SHENZHEN BWAY TECH CO., LTD.**, Baoan Area, Shenzhen, Guangdong (CN)

(72) Inventor: **Xiu Zhu Zhang**, Shenzhen (CN)

(73) Assignee: **SHENZHEN BWAY TECH CO., LTD.**, Shenzhen, Guangdong (CN)

(**) Term: **15 Years**

(21) Appl. No.: **29/635,670**

(22) Filed: **Feb. 1, 2018**

(51) LOC (12) Cl. **13-02**

(52) U.S. Cl.

USPC **D13/108**; D14/253; D12/415
